WIRE AND STRAND SATURATING TANK

Anthony P. Hinsky, Brooklyn, N. Y., assignor to
Pyro Products Corporation, Brooklyn, N. Y., a
corporation of New York

Application June 9, 1939, Serial No. 278,224

20 Claims. (Cl. 91—32)

This invention relates to tanks designed particularly for use in saturating insulated wires and suitable for saturating any type or kind of elongated strand in the application of saturants or compositions thereto and including the application of heated materials of this type and kind; and the object of the invention is to provide a tank of the character described employing one or more drums with means for supporting the drum or drums in a fully submerged position within the saturating or coating solution arranged in the tank as well as to support the drum or drums in a partially raised position for threading a wire or strand thereon, and still further in supporting the drum or drums in a position above the tank in cleaning out the tank and for repair or other purposes; a further object being to provide means engaging the drum or drums in the partially raised position for rotating the same in winding a wire or strand on the drum or drums; a further object being to provide drums perforated to provide means for applying the coating material to the surfaces of the wire or strand engaging the drum when wound thereon; a further object being to provide a rounded bottom to the tank so as to dispose the lower portion of the drum or drums in close proximity to the bottom of the tank to insure, by the rotation of the drum, a constant agitation of the coating material at the bottom of the tank while also checking or harnessing, to some degree, the current or eddy of the material which has a tendency to be thrown away from the drum in the rotation of the drum in the coating material; a further object being to provide adjustable means for stopping the submerged movement of the drum into the tank to maintain a predetermined position of the drum within the tank; a further object being to provide drum lifting and lowering means which is self-locking so as to maintain the drum in different positions of adjustment; a still further object being to provide independent compartments in a tank for the reception of independent drums, and to the provision of a supply tank intermediate the separate compartments for replenishing the supply of coating material to the respective compartments; and with these and other objects in view, the invention consists in an apparatus of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable

reference characters in each of the views, and in which:

Fig. 1 is a sectional view through a tank made according to my invention showing parts in two different dotted line positions.

Fig. 2 is a plan view of the construction shown in Fig. 1 with parts of the construction broken away and in section, and

Fig. 3 is a diagrammatic plan view showing another adaptation of the invention.

In the treatment of insulated conductors in applying saturants and the like thereto, it has been a common practice to pass the conductor several times around a partially submerged drum arranged upon a relatively fixed axis in the tank, or to pass the conductor around spaced sheaves arranged in a long rectangular tank. It is the purpose of my invention to overcome objectionable features to structures of this type and kind by providing a more compact tank which will occupy less floor space. Further it is the purpose of my invention to provide means for moving a drum into several positions with respect to the tank; in other words, in changing the position of the axis of rotation of the drum so that the drum may be fully submerged in the coating material arranged in the tank, raised slightly for the purpose of wrapping or winding a conductor or strand thereon a number of times, and still further to moving the drum above the upper surface of the tank. In addition to the foregoing it is another feature of my apparatus to so construct and arrange the walls of the tank with respect to the drum as to establish a more constant contact of the coating material with the wire or strand on the drum in rotating the drum at high speeds to provide for the coating or processing of conductors or strands which are fed at high speeds.

In Figs. 1 and 2 of the drawing I have shown, for the purpose of illustrating one adaptation of my invention, an apparatus employing two drums operating in a single tank construction. It will be understood, however, that single or multiple units may be employed depending largely upon the requirements of a manufacturer. In the drawing, 10 represents a suitable frame which may be supported in any desired manner, and at 11 is shown a tank having a rounded bottom 12. At one end of the tank adjacent the upper portion thereof are supported brackets 13 which are substantially yoke-shaped in form having spaced bearings 14 for shafts 15, and bearings 16 for worm shafts 17 to which are secured worms 18. The outer ends of the shafts 17 have cranks 19

by means of which the worms 18 may be rotated to rotate worm wheels 20 secured to the shafts 15.

It will be apparent from a consideration of Fig. 2 of the drawing that each bracket 13 supports an independent operating unit, and as these units are identical in construction, like references will represent like parts. Each unit is adapted to control the operation of independent drums 21, 21a. Secured to each shaft 15 is a pair of arms 22 of the general contour as seen in Fig. 1 of the drawing. Supported in connection with the free end of each pair of arms is a shaft 23 upon which the respective drums 21, 21a are free to rotate. Each drum also has secured to one side thereof a large gear 24 by means of which the drums may be manually rotated when raised into the position shown at X in dotted lines in Fig. 1 of the drawing, in which position the gears 24 mesh with pinions 25 which in turn mesh with other pinions 26 on a shaft rotated through the medium of a hand crank 27. The parts 25, 26 and 27 are supported upon the upper portion of the sides of the tank, as clearly indicated in Figs. 1 and 2 of the drawing, so as to maintain proper registering position with respect to the gears 24 when moved into raised position, while at the same time permitting the free passage of the drums from the position at X to the position shown at X2 in Fig. 1 of the drawing as well as the return of the drums to the normal submerged position shown in full lines in Fig. 1.

From the foregoing description, it will be apparent that the drums are moved into their raised and lowered positions through the rotation of the crank 19, and the worm 18 and worm wheel 20. This structure forms a self-supporting lock for the drum in the several positions of adjustment thereof.

I also provide at each side portion of the tank a bracket 28 in which an adjustment stop screw 29 is supported to engage one of the arms 22 of each pair to limit and control the normal or fully submerged position of the drums in the tank. In this way, proper relationship of the drums with respect to the bottom of the tank may be maintained or may be varied to suit different runs of material in providing the desired or most suitable clearance of the drums with respect to the bottom of the tank. When the drums are fully submerged, a level of the coating material is maintained in the tank well above the upper part of the drum as is indicated at 30 in Fig. 1 of the drawing so that the drum is fully submerged.

The drums in the construction shown, are of identical construction, therefore, the brief description of one will apply to both. Each drum is formed from sheet metal side discs 31, 32 having an inner solid wall ring 33, joining opposed discs 31, 32, and an outer larger diameter perforated wall ring 34 so as to form, within the central portion of the drum, an air-tight chamber 35, admission to which is controlled by plugs 36 and an annular chamber 37 between the rings 33 and 34. The side discs have perforations 38 opening into the chamber 37 so as to provide a free circulation of the material 30 through the chambers 37 to provide for a more thorough contact of the material with the wire or other strands wound on the ring 34 of each drum, even though the windings of the insulated wire or strand are arranged in close proximity to each other on the drum.

Each outer ring 34 upon which the wire or strands are wound are also preferably tapered from the discs 32 to the discs 31 so that the in-

coming wire or strands as at 39, 39a after passing over a guide sheave 40, will extend onto the wider diameter of the tapered ring 34 and automatically feed in the direction of the discs 31 and then will be fed off from the drums and pass over other guide sheaves 41 and then passed through die or other wipers 42 supported upon the upwardly inclined portion 43 of the tank and frame so that the surplus removed material 30 will pass back into the tank, as will be apparent. At this time it will be understood that any type and kind of wipers or dies may be employed, the illustration in the accompanying drawing being simply diagrammatic.

Supported in connection with one arm 22 in each pair is a guide finger or arm 44 for maintaining a proper feed of the wire or strand upon entering each of the drums and to prevent overlapping of the wire or strand at one end of the drum. In the present illustration, a few turns of the wire or strand are shown at one end of each drum, and these turns are shown in spaced relation to each other. In some instances, however, especially in using larger diameter wires or strands, a closer relationship of the wire or strands on the drum may result.

It will be understood that in using dual drums arranged in a single tank, as illustrated in Fig. 2 of the drawing, each drum is independently controlled and operated, and the control and operation of one drum will in no way affect the control and operation of the other. With a construction of this type and kind it will also appear that as the wire or strand enters the tank it is fully and completely enveloped by the coating material or saturant 30 before it engages the drum. In like manner it is again fully enveloped by the material on leaving the drum and before passing over the sheave 41 and through the die 42.

It will also be apparent that each drum may operate in an independent material by simply partitioning the tank centrally and longitudinally thereof. Still further, and as diagrammatically illustrated in Fig. 3 of the drawing, a tank 12a may have double partitions 45 to form within and between the separate chambers 46, 47 of the tank, a reserve chamber 48, or this chamber may be partitioned centrally and transversely as seen at 49 to form independent compartments 50, 50a, especially when independent or different materials are to be used in the chambers 46, 47.

In Fig. 3 of the drawing, 51, 51a represent, diagrammatically, the independent drums similar in all respects to the drums 21, 21a, and all of the supporting and operating mechanism has been omitted from the illustration in Fig. 3 of the drawing as there is no need of duplicating this showing to simply illustrate a different type of tank construction which can be employed.

When saturants, compounds or coating materials are to be applied hot or under predetermined temperatures, suitable heating mediums will be provided below the tank or tanks. To diagrammatically illustrate one type of heating medium, I have shown in Fig. 1 of the drawing in cross section, two gas burner tubes 52 disposed beneath the tank 11 and extending transversely of the apparatus. It will of course be understood that suitable and well known means will be provided to maintain substantially constant temperature of the material employed, and where different materials are employed in independent tanks, independent heating mediums and controls will of course be provided.

At 52a in Fig. 3 of the drawing I have dia-

grammatically illustrated the burner tubes protruding from one end of the tank.

In the operation of the apparatus, it will appear from a consideration of Fig. 1 of the drawing that the flow or eddy of the coating material caused by the fast rotation of the drum or drums, is checked and retarded by the rounded contour of the bottom of the tank, and in maintaining the walls of the tank in close proximity to the periphery of the drum and by operating the drum or drums in the fully submerged position, oxidation is substantially eliminated in that no air is drawn into the material by the drums, as would be the case in conventional methods of procedure where a drum is partially submerged. Further, the use of the perforated wall structure 34 on the drum in the chamber 37 with the admission ports 38, provides for the circulation of the material through the periphery of the drum to contact the underside of the wire or strand wound thereon. In fact, this construction will set up an independent circulation within the peripheral portion of the drum and produce in effect a flow of material heretofore unknown in apparatus of this type and kind.

While an independent reserve tank may be used to replenish the supply of the coating or saturating material, especially when the same is heated, and is desirable from the standpoint of maintaining a substantially constant temperature, it will appear that by associating the reserve tank or tanks with a complete unit as in Fig. 3 of the drawing and utilizing the same heating medium, a more efficient and practical construction is provided. In this way the unheated material may be fed into the reserve tank or tanks from time to time without having any detrimental effect upon the temperature of the material or materials in the associated tank or tanks employed in a complete unit.

It will be understood that with my novel method of quickly raising and lowering the drums with respect to the tank, the operation of stringing or winding a new wire or strand on the drum can be quickly performed by simply raising the drum in the position shown at X and operating the cranks 27. In like manner, when it is desired to clean out or repair the apparatus, the drum may be raised into position as shown at X2 in Fig. 1, which will render the tank accessible for cleaning or other purposes prior to the introduction of new coating materials into the tank. This is especially true in introducing different types and kinds of materials in the tank from a standpoint of consistency or color.

It will also appear that the rounded bottom tank in addition to performing the advantageous functions before named, produces a tank which may be more readily cleaned than the more conventional flat bottom rectangular tanks. By reason of the foregoing facts, it will be apparent that a shop may operate on different runs of material or in applying different types and kinds of coatings on wires or strands with a minimum number of machines or apparatus, eliminating the necessity of maintaining one apparatus for one type and kind of coating or saturant treatment to wires or strands of the type under consideration.

It will also be apparent that in the treatment of certain types or kinds of strand-like workpieces, a continuous processing may be provided wherein the workpiece passes from one tank unit of the type and kind herein described, into one or more other units in applying different coatings

or compounds thereto in one continuous process. In this connection, it will also be apparent that while I have shown in the combined unit, as in Fig. 2 of the drawing, the entrance of the workpiece or strand at one common side or end of the machine with a discharge at one common side or end thereof, that one of these units may be reserved so that one strand enters at one side and the other strand at the opposed side.

10 This is simply a matter of arrangement and adaptation of the invention to suit different possible uses thereof.

It will be understood that as in other tanks of the type and kind under consideration, the insulated wire conductor, or other strands, is drawn through the apparatus, and this drawing operation of the strand by reason of the number of turns upon the drum or drums causes the latter to be rotated. In this connection it will also appear that the adjustment or movement of the drums with respect to the tank will in no way interfere with the drawing operation of the workpiece. In this connection it will be understood that in some instances, it might be desirable to operate the drum in a partially submerged position, and in such instances other means will be provided for guiding the take-off of the workpiece or the strand from the drum to compensate for the different positions thereof. It will of course be apparent that my invention is by no means restricted to the specific structure herein disclosed for supporting and operating the drums or for mounting the same or to the other structural details of the apparatus as shown, as this would be varied and modified to suit different adaptations and uses of the invention.

Having fully described my invention, what I claim as new and desire to secure by Letters Patent, is:

40 1. An apparatus for the treatment and coating of strand-like workpieces comprising a tank, a rotatable member around which the workpiece passes, means movably supporting said rotatable member to arrange said member in a fully submerged position within a coating material arranged in said tank and for raising said member into a partially submerged position or entirely out of the tank, adjustable means for limiting the movement of said member into the tank, interengaging means on said member and tank for manually rotating said member when the same is supported in a partially submerged position, means for guiding the workpiece strand into and out of the tank, means for removing surplus material from the workpiece before passing beyond the boundaries of the tank, and an elongated part pivotally secured to said first-named means and tangentially contacting said rotatable member for guiding the first turn of the workpiece on said member.

60 2. An apparatus for the treatment and coating of strand-like workpieces comprising a tank, a rotatable member around which the workpiece passes, means movably supporting said rotatable member to arrange said member in a fully submerged position within a coating material arranged in said tank and for raising said member into a partially submerged position or entirely out of the tank, said rotatable member comprising a drum having an outer perforated ring upon which the workpiece is wound, and means forming an annular chamber within said perforated ring exposed to the material in the tank for applying material in said tank to the undersurfaces of the workpiece arranged on the ring of said drum.

3. An apparatus for the treatment and coating of strand-like workpieces comprising a tank, a rotatable member around which the workpiece passes, means movably supporting said rotatable member to arrange said member in a fully submerged position within a coating material arranged in said tank and for raising said member into a partially submerged position or entirely out of the tank, said rotatable member comprising a drum having an outer perforated ring upon which the workpiece is wound, means forming an annular chamber within said perforated ring exposed to the material in the tank for applying material in said tank to the undersurfaces of the workpiece arranged on the ring of said drum, and said first named means comprising a pair of arms pivotally supported in connection with the tank, with the drum freely rotatable in the free end of said arms and a worm and worm wheel for actuating said arms in moving the drum into different positions with respect to said tank.

4. An apparatus for coating elongated strand-like workpieces comprising a tank, a rotatable drum around which the workpiece is wound a number of times, and means supporting the drum with respect to the tank for pivotal movement in a predetermined path from a position fully submerged within a coating material arranged in the tank to at least a partially submerged position with respect to said material, and unitary control means adapted both to impart desired pivotal movement to said drum and to support the drum in different positions of adjustment with respect to the tank.

5. An apparatus for coating elongated strand-like workpieces comprising a tank, a rotatable drum around which the workpiece is wound a number of times, means supporting the drum with respect to the tank for pivotal movement in a predetermined path from a position fully submerged within a coating material arranged in the tank to at least a partially submerged position with respect to said material, unitary control means adapted both to impart desired pivotal movement to said drum and to support the drum in different positions of adjustment with respect to the tank, and means in the path of movement of said drum and cooperating with the drum in one position of adjustment thereof for rotating said drum independent of the rotation thereof by said workpiece.

6. An apparatus for coating elongated strand-like workpieces comprising a tank, a rotatable drum around which the workpiece is wound a number of times, means supporting the drum with respect to the tank for pivotal movement in a predetermined path from a position fully submerged within a coating material arranged in the tank to at least a partially submerged position with respect to said material, unitary control means adapted both to impart desired pivotal movement to said drum and to support the drum in different positions of adjustment with respect to the tank, means in the path of movement of said drum and cooperating with the drum in one position of adjustment thereof for rotating said drum independent of the rotation thereof by said workpiece, and adjustable means limiting the fully submerged position of the drum in said tank.

7. In a tank for treating and coating insulated conductors, a drum around which a conductor is wound, a pair of arms pivotally supported in connection with an upper edge portion of said tank, means at the free ends of the arms for rotatably supporting a drum in connection there-

with, means for actuating said arms to swing the drum relatively to said upper edge portion of the tank whereby said drum may be supported in a fully submerged position within treating material arranged in the tank chamber and raised into at least a partially submerged position with respect to said material.

8. In an apparatus for treating and coating insulated wires, a tank in which coating or treating material is arranged and maintained at a predetermined level, a drum supported in fully submerged position within the material arranged in said tank for free rotary movement in the feed of an insulated wire through the tank and around said drum, the peripheral surface of the drum engaged by the insulated wire being inclined slightly with respect to the axis of said drum, said surface having transversely and circumferentially spaced perforations, an annular member arranged inwardly of said surface, and in uniformly spaced relation thereto defining an annular chamber within said drum, and means on the drum admitting the material in said tank to said annular chamber to extend outwardly through said perforated surface thereby contacting the underside of the insulated conductor arranged on the drum.

9. An apparatus for the treatment and coating of strand-like workpieces, said apparatus comprising a tank, a rotatable member around which a workpiece is adapted to pass, means at an upper edge portion of the tank pivotally supporting said rotatable member in connection with said tank in a manner to provide swinging movement of said member with respect to said upper edge portion from a position wholly within the tank to a position completely removed from the tank, and means adjacent the pivotal support of said member for controlling the swinging movement thereof.

10. An apparatus for the treatment and coating of strand-like workpieces, said apparatus comprising a tank, a rotatable member around which a workpiece is adapted to pass, means at an upper edge portion of the tank pivotally supporting said rotatable member in connection with said tank in a manner to provide swinging movement of said member with respect to said upper edge portion from a position wholly within the tank to a position completely removed from the tank, and means adjacent the pivotal support of said member for controlling the swinging movement thereof, said last-named means comprising a worm and worm gear arranged to provide intended movement of said member and to support said member in any position of pivotal adjustment thereof.

11. An apparatus for the treatment and coating of strand-like workpieces, said apparatus comprising a tank, a rotatable member around which a workpiece is adapted to pass, means at an upper edge portion of the tank pivotally supporting said rotatable member in connection with said tank in a manner to provide swinging movement of said member with respect to said upper edge portion from a position wholly within the tank to a position completely removed from the tank, means adjacent the pivotal support of said member for controlling the swinging movement thereof, said last-named means comprising a worm and worm gear arranged to provide intended movement of said member and to support said member in any position of pivotal adjustment thereof, and adjustable means for limiting the movement of said member into the tank.

12. An apparatus for the treatment and coating of strand-like workpieces, said apparatus comprising a tank, a rotatable member around which a workpiece is adapted to pass, means at an upper edge portion of the tank pivotally supporting said rotatable member in connection with said tank in a manner to provide swinging movement of said member with respect to said upper edge portion from a position wholly within the tank to a position completely removed from the tank, means adjacent the pivotal support of said member for controlling the swinging movement thereof, adjustable means for limiting the movement of said member into the tank, and interengaging means on said member and tank for manually rotating said member when the same is supported in a position partially removed from the tank.

13. An apparatus for coating strand-like workpieces of the character described, said apparatus comprising a tank, a pair of drums freely rotatable about separate movable axes, means mounting said drums for pivotal movement about a common axis adjacent one upper edge of the tank, independent control means for moving the drums about said last-named axis between positions fully submerged in the treating material in the tank and positions at least partially removed from the tank, and said control means also forming means for retaining the drums in any desired positions of adjustment.

14. An apparatus for coating strand-like workpieces of the character described, said apparatus comprising a tank, a pair of drums freely rotatable about separate movable axes, means mounting said drums for pivotal movement about a common axis adjacent one upper edge of the tank, independent control means for moving the drums about said last-named axis between positions fully submerged in the treating material in the tank, and positions at least partially removed from the tank, said control means also forming means for retaining the drums in any desired positions of adjustment, and independent means cooperating with the respective drums in predetermined positions of adjustment thereof for independently and manually rotating the drums.

15. An apparatus for coating strand-like workpieces of the character described, said apparatus comprising a tank, a pair of drums freely rotatable about separate movable axes, means mounting said drums for pivotal movement about a common axis adjacent one upper edge of the tank, independent control means for moving the drums about said last-named axis between positions fully submerged in the treating material in the tank and positions at least partially removed from the tank, said control means also forming means for retaining the drums in any desired positions of adjustment, independent means cooperating with the respective drums in predetermined positions of adjustment thereof for independently and manually rotating the drums, and adjustable means controlling the fully submerged position of each drum.

16. An apparatus for coating strand-like workpieces of the character described, said apparatus comprising a tank, a pair of drums freely rotatable about separate movable axes, means mounting said drums for pivotal movement about a common axis adjacent one upper edge of the tank, independent control means for moving the

drums about said last-named axis between positions fully submerged in the treating material in the tank and positions at least partially removed from the tank, said control means also forming means for retaining the drums in any desired positions of adjustment, and the tank being subdivided intermediate said drums to provide independent chambers in the tank in which the separate drums operate.

17. An apparatus for coating strand-like workpieces of the character described, said apparatus comprising a tank, a pair of drums freely rotatable about separate movable axes, means mounting said drums for pivotal movement about a common axis adjacent one upper edge of the tank, independent control means for moving the drums about said last-named axis between positions fully submerged in the treating material in the tank and positions at least partially removed from the tank, said control means also forming means for retaining the drums in any desired positions of the adjustment, the tank being subdivided intermediate said drums to provide independent chambers in the tank in which the separate drums operate, and the subdivision of the tank comprising a reserve compartment for the storage of coating material to be supplied to the separate chambers of the tank.

18. An apparatus for coating strand-like workpieces of the character described, said apparatus comprising a tank, a pair of drums freely rotatable about separate movable axes, means mounting said drums for pivotal movement about a common axis adjacent one upper edge of the tank, independent control means for moving the drums about said last-named axis between positions fully submerged in the treating material in the tank and positions at least partially removed from the tank, said control means also forming means for retaining the drums in any desired positions of the adjustment, the tank being subdivided intermediate said drums to provide independent chambers in the tank in which the separate drums operate, the subdivision of the tank comprising a reserve compartment for the storage of coating material to be supplied to the separate chambers of the tank, and means for heating the coating material in the compartment and chambers of the tank.

19. In a strand treatment tank of the character described, means pivotally movable at the upper edge portion of the tank and including a rotatable member movable into and out of the tank to positively support a relatively long length of a strand in a number of turns wound around said member within and completely submerged in a solution arranged in the tank, and means for actuating the first named means to move said member together with the strand supported thereon into other positions partially submerged in the tank and entirely out of the tank.

20. An apparatus for the treatment and coating of strand-like workpieces, said apparatus comprising a tank, a wide rotatable member around which a workpiece is adapted to pass in a plurality of spiral turns across the width thereof, and means pivoted to the upper portion of the tank to support said member in connection with said tank in a manner to provide swinging movement of said member with the workpiece thereon from a position wholly within the tank to a position completely removed from the tank.

ANTHONY P. HINSKY.
